GLASS BUILDING BLOCK UNIT

Ford Pennell, Webster Groves, Mo., assignor to Jane Booth Pennell, Webster Groves, Mo.

Original application June 27, 1949, Serial No. 101,535, now Patent No. 2,714,816, dated August 9, 1955. Divided and this application February 3, 1955, Serial No. 489,713

6 Claims. (Cl. 88—60)

The invention relates to building materials and more particularly to those used in translucent or transparent wall structures, such as blocks of glass, plastic and similar materials. This application is a division of a copending application, Serial No. 101,535, now Patent No. 2,714,816, filed June 27, 1949.

One object of the invention is to block or materially reduce transmission of the direct light and heat rays of the sun, striking the block or wall, into a building, when the sun is well above the horizon and at the same time transmit into the building those rays which are reflected from the ground and surroundings of the building.

Another object is to pass substantially all the direct rays of the sun, striking the block or wall, into the building as the sun approaches the horizon.

The invention contemplates a building block, or a building wall or section thereof, which may include a plurality of building blocks, with upright exterior side faces. One of the side faces consists of corrugations substantially lengthwise and substantially parallel to the plane of the block base which is arranged to stably support the block and its load, so that when placed in a wall the corrugation extends substantially parallel to the horizon. The corrugation surfaces face generally away from the body of the block and generally toward the planes of the top face and base. These general objects may be attained by corrugations having planar or arcuate surfaces vertically of the block and in the application Serial No. 101,535, now Patent No. 2,714,816, from which the present application is divided, the arrangement of planar surfaces is described in detail and claimed. This application is directed to blocks with corrugations having surfaces which are arcuate, at least in part.

Those corrugation surfaces facing generally towards the plane of the top face, or at least the major portions thereof, are coated with a substance which prevents or materially reduces transmission of the light and heat rays. Other corrugation surface portions facing generally toward the plane of the base are substantially translucent and permit rays scattered or reflected from the surroundings of the building to pass therethrough. The arrangement of the corrugations may be varied to block and to pass desired quantities of direct rays and reflected rays through the wall structure, and the coating thereon may be such as to pass desired proportions of light and heat rays.

The above and other detailed objects of the invention, as will appear below, are attained by the structure shown in the accompanying drawings, which structure is intended to be illustrative and not exclusive of other arrangements providing the general inventive principle. In these drawings:

Figure 1 is a perspective view of a building block constructed according to the invention.

Figure 2 is a transverse vertical section, drawn to an enlarged scale, and taken approximately on line 2—2 of Fig. 1.

Figure 3 is a detailed vertical section, drawn to an

2

enlarged scale of a portion of the right-hand face of the building block shown in Figure 2.

Figures 4—8 are vertical sections corresponding to the right-hand portion of Figure 2 and show other embodiments of the invention.

Figure 9 is a diagrammatic showing of several other arrangements of the corrugated surfaces in the outer faces of building blocks according to the invention.

A building block constructed according to the invention, of glass, plastic or other transparent or translucent material, comprises an upright exterior front or side face 1, an upright exterior rear or side face 2, a top face 3, end faces 5 and 6, and a base or bottom face 4 upon which the block and its load may be stably supported.

15 The block preferably is hollow and may be formed by uniting two separately molded units and fusing them together as indicated at 7. Top and bottom faces 3 and 4 and end faces 5 and 6 may be grooved, as shown, to receive mortar to bind the block to upper and lower blocks 20 in building a wall structure. Top and bottom faces preferably are positioned in horizontal planes when the blocks are assembled to one another in building a wall. Front face 1 has corrugations with longitudinally straight surfaces extending substantially parallel to the planes of 25 the top face 3 and base 4 and preferably, but not necessarily, from end face 5 to end face 6.

In the embodiment shown in Figures 1, 2, and 3, the portions of the corrugation surfaces facing generally downwardly toward the plane of base 4 are translucent 30 so that they may transmit rays of light from the center or rays of light reflected from below or near the horizon. Portions 16 of the corrugation surfaces face generally upwardly toward the plane of top face 3 and are treated to materially reduce transmission of rays of light 35 from the center.

The translucent portion 15 of each corrugation extends downwardly and inwardly in a quadrant of a circle. The treated surface 16 of each corrugation extends downwardly and outwardly in an arc of a circle of approximately 45° 40 and terminates in a plane inclined at an angle of approximately 45° to the plane of the base.

The relative areas of translucent portions 15 and treated portions 16 are such that, when the sun is at an angle of approximately 45° or more above the horizon, portions 15 are shaded from direct rays of the sun by portions 16 and pass only the rays reflected or scattered from portions 16 or from surrounding objects.

Downwardly facing surfaces 15 are transparent or translucent and pass light and heat rays of the sun. Upwardly facing surfaces 16 are rendered substantially impervious to the rays of the sun by coating the surfaces with a light and heat reflecting or filtering substance. Surfaces 16 may be coated with a metallic mirror finish or a white enamel finish, which would reflect substantially all the light and heat rays, or the surfaces may be coated with a blue filtering glass finish, which would permit a substantial quantity of the light rays to pass but be at least partially impervious to the heat rays, or the surfaces may be coated with a black enamel finish which 50 would absorb a substantial quantity of the heat rays and be impervious to the light rays. Preferably the coating is treated so that it becomes an integral part of the building block.

Direct rays of the sun striking upwardly facing surfaces 65 16 are reflected, scattered or absorbed, depending upon the coating used. Downwardly facing surfaces 15 are immediately below the level of the outer extremities of the respective associated surfaces 16 and extend inwardly from such extremities so that a straight line 70 inclined 45° from the vertical and passing by or just clearing the outer extremity of each surface 16 will avoid striking the associated surface 15. Hence, when the

sun is 45° or more above the horizon, surfaces 15 are shaded from direct rays of the sun and pass only rays reflected or scattered from surfaces 16, or from surrounding objects.

When the sun is less than 45° above the horizon, the direct rays of the sun strike the downwardly facing translucent surfaces 15 and, as the sun approaches the horizon, increasing quantities of the direct rays of the sun pass through the block.

In Figure 4, front face 1e has convex corrugation surfaces 17 facing generally downwardly and outwardly of the block toward the plane of base 4e, and convex corrugation surfaces 18 facing generally upwardly and outwardly of the block toward the plane of top face 3e. Each surface 17, 18 forms an arc of a circle. The upper and lower ends of surfaces 17 are inclined at angles of approximately 60° and 15°, respectively, to the planes of top face 3e and base 4e. The upper and lower ends of surfaces 18 are inclined at angles of approximately 30° and 70°, respectively, to the planes of the top face and base. In other words, the tangents to the arcuate surfaces 18 vary from 60° to 20° from a perpendicular to the plane of the base.

Surfaces 17 are translucent and surfaces 18 are coated with a substance which blocks or materially reduces transmission of the sun's rays and shade surfaces 17 from the direct rays of the sun, when the sun is 60° or more above the horizon, so that surfaces 17 pass only reflected or scattered rays.

In Figure 5 front face 1f has concave corrugation surfaces 19 facing generally downwardly and outwardly of the block toward the plane of base 4f, and concave corrugation surfaces 20 facing generally upwardly and outwardly of the block toward the plane of top face 3f. Each surface 19 and 20 forms the arc of a circle. The upper and lower ends of surfaces 19 are inclined at angles of approximately 15° and 60°, respectively, to the planes of the top face 3f and base 4f. The upper and lower ends of surfaces 20 are inclined at angles of approximately 70° and 30°, respectively, to the planes of the top face and base or between 20° and 60° from a perpendicular to the plane of the base. Surfaces 19 are translucent and surfaces 20 are coated with a substance substantially impervious to the rays of the sun and shade surfaces 19 from the direct rays of the sun, when the sun is 45° or more above the horizon, so that surfaces 19 pass only reflected or scattered rays.

In Figure 6 the corrugation surfaces in front face 1g are concave and semi-circular. The upper quadrant 21 of each corrugation surface faces generally downwardly and outwardly towards the plane of base 4g and is translucent. The lower quadrant 22 of each corrugation surface faces generally upwardly and outwardly towards the plane of the top face 3g and is substantially impervious to the sun's rays. Portions 22 shade the translucent portions 21 from the direct rays of the sun, when the sun is at an angle of 45° or more above the horizon, so that portions 21 pass only reflected or scattered rays.

The arrangement shown in Figure 7 is substantially the same as the arrangement shown in Figure 6, except that each corrugation surface in front face 1h in Figure 7 is less than a semicircle. Impervious portion 23 of each corrugation extends about 15° above the midpoint of the arc and shades the translucent portion 24 from the direct rays of the sun when the sun is at an angle of 45° or more above the horizon. The lower ends of portions 23 and the upper ends of portions 24 are inclined at angles of approximately 25° to the planes of the top face 3h and base 4h.

In Figure 8 the corrugation surfaces in front face 1k are convex and semicircular. The upper quadrant 25 of each corrugation surface faces generally upwardly and outwardly toward the plane of top face 3k. Quadrant 25 and the arc 25a adjacent thereto, extending approximately 20° below the midpoint of the arc, are im-

pervious to the sun's rays and the remaining lower portion 26 of the corrugation surface, facing generally downwardly and outwardly of the block toward the base 4k, is translucent. Portions 25, 25a shade translucent portions 26 from the direct rays of the sun when the sun is 70° or more above the horizon or less than 20° from a perpendicular to the plane of the base.

Figure 9 shows diagrammatically several other possible combinations of plane and arcuate corrugation surfaces. At A, each upwardly facing surface a^2 is planar and is inclined at an angle of 45° to the plane of the base. Each downwardly facing surface a^3 is concave and the upper end of each surface is inclined at an angle of 25° and the lower end of each surface is inclined at an angle of 70° to the plane of the base. At B, each upwardly facing surface b^2 is concave and the upper end of the surface is inclined at an angle of 70° and the lower end of the surface is inclined at an angle of 25° to the plane of the base. Each downwardly facing surface b^3 is planar and is inclined at an angle of 45° to the plane of the base. At C, each upwardly facing surface c^2 is convex and the upper end of the surface is inclined at an angle of 25° and the lower end is inclined at an angle of 70° to the plane of the base or 20° from a perpendicular to the plane of the base. Each downwardly facing surface c^3 is planar and is inclined at an angle of 45° to the plane of the base. At D, each upwardly facing surface d^2 is planar and is inclined at an angle of 45° to the plane of the base. Each downwardly facing surface d^3 is convex and the upper end of the surface is inclined at an angle of 70° to the plane of the base or 20° from a perpendicular to the plane of the base and the lower end of the surface is inclined at an angle of 25° to the plane of the base or 55° from a perpendicular to the plane of the base. Upwardly facing surfaces a^2, b^2, c^2, d^2 are treated to materially reduce transmission of the rays of the sun.

The amount of light and heat from the direct and reflected rays of the sun which is permitted to pass through the wall structure may be controlled by the configuration and angular arrangement of the corrugations and by the nature of the coating on the upwardly facing surfaces. The smaller the angle between successive opposing corrugation surfaces on the exterior of the block, the more light will be reflected into the translucent downwardly facing surfaces. The smaller the angle between the downwardly facing translucent surfaces and the vertical, the higher the angle at which the sun's rays will begin to pass through the downwardly facing translucent surfaces. The smaller the angle between the upwardly facing impervious surfaces and the vertical, the greater will be the proportion of impervious surfaces to translucent surfaces provided the angle between successive opposing surfaces is fixed, and the smaller will be the percentage of rays transmitted to the total rays striking the building block.

As explained above, the nature of the coating on the upwardly facing surfaces determines the relative quantities of direct light and heat rays passing through these surfaces.

The wall structure, when in the northern hemisphere and facing toward the south, will permit more direct rays of the sun to pass therethrough in the winter time when the warmth and light are needed, and to reflect and scatter more direct rays of the sun during the summer to reduce glare and heat transmission.

The details of the invention described and illustrated may be varied without departing from the spirit of the invention, and the exclusive use of those modifications coming within the scope of the claims is contemplated.

What is claimed is:

1. An integral hollow building block of translucent material for a building wall, having an exterior top face, an exterior base upon which the block and its load may be stably supported, and generally upright exterior side

faces and end faces, one of said side faces having corrugations each running substantially parallel to the plane of said base and substantially from end face to end face, said corrugations being arcuate, at least in part, vertically of the block, a major portion of a surface of each corrugation facing generally outwardly of the block and generally upwardly toward the plane of said top face and being treated to materially reduce passage of the sun's rays therethrough, and substantially all of the remaining portions of the surface of each corrugation facing generally outwardly of the block and generally downwardly toward the plane of said base and consisting of a translucent area providing for the passage of sun rays from the exterior of the block to the interior thereof and being positioned inwardly of the block from the outer extremity of a corrugation immediately above the translucent area, the projections of the corrugations and their vertical spacing from each other being such that a straight line inclined downwardly and inwardly of the block at an angle of less than 20° from a perpendicular to the plane of said base and contacting said outer extremity will strike a treated surface of the next lower corrugation, and that a straight line inclined upwardly and inwardly of the block from below the horizontal and contacting said outer extremity will strike a translucent area of the next higher corrugation.

2. An integral hollow building block of translucent material for a building wall according to claim 1, in which all of the corrugation surfaces are convex exteriorly of the corrugated side face and that portion of each corrugation above the horizontal is coated to intercept sun rays directed downwardly from the horizontal and prevent the passage of said rays by reflecting them outwardly of the block exterior face.

3. An integral hollow building block of translucent material for a building wall according to claim 1, in which all of the corrugation surfaces are concave exteriorly of the corrugated side face and that portion of each corrugation above the horizontal is coated to intercept sun rays directed downwardly from the horizontal and prevent the passage of said rays by reflecting them outwardly of the block exterior face.

4. Structure as described in claim 1 in which the portions of each corrugation surface facing toward the plane of the structure top face are substantially planar and are inclined at an angle between 25° and 70° to the plane of the top face and the portions of each corrugation surface facing toward the plane of the structure base are arcuate in vertical section.

5. Structure as described in claim 1 in which a vertical cross section through the corrugations shows each corrugation surface of concave arcuate contour with substantially the entire main portions of each corrugation surface inclined to the plane of the structure base at angles of between 25° and 70°.

10 6. A block of glass-like material for a building wall, having a body with an exterior top face, an exterior base upon which the block and its load may be stably supported, and upright exterior side faces, one of said side faces comprising a plurality of corrugations each extending substantially straight across the block and substantially parallel to said base, each corrugation having arcuate surfaces facing generally away from the block body, substantially all portions of said surfaces facing 15 in directions inclined at angles of between 25° to 70° to the planes of said top face and base, the corrugation surfaces facing generally toward the plane of said base being light transmitting, and the corrugation surfaces facing generally toward the plane of said top face being coated to reduce the transmission of sun rays striking the exterior of the corrugation from above the horizontal.
